UNITED STATES PATENT OFFICE.

JEAN PERDREAU, OF PARIS, FRANCE, ASSIGNOR TO SOCIETE ANONYME MARINONI
(MACHINES ET MATERIEL POUR L'IMPRIMERIE ET LES INDUSTRIES ANNEXES)
OF PARIS, FRANCE.

COMPENSATING DEVICE.

Application filed May 18, 1926, Serial No. 109,988, and in France April 30, 1926.

Printing machines of certain classes are in use in which the thickness of the operative part of the printing cylinder is variable within restricted limits.

For this reason, the diameter of the said cylinder will not be uniform, and it may be somewhat larger or smaller than the pitch circle of the gear wheel secured to the cylinder which it actuates. In either case, the result will be a certain friction of the printing cylinder upon the pressure cylinder which is in contact therewith, which is prejudicial to the printing work produced by the machine.

In particular, in the rotary printing machines for sunken relief work, such as intaglio rotogravure, heliogravure or the like, the printing cylinders usually employed have the form of a steel core which is covered with a thin envelope of electrolytic copper, upon which the printing work is engraved. When the printing operation is completed, the said envelope is treated by the polishing process, whereby the thickness of the engraved metal is removed.

In this manner, each time the operative surface is renewed, the diameter of the cylinder will be reduced.

This disadvantage has been obviated in practice by modifying the facing of the pressure cylinder for each change in the diameter of the printing cylinder, but this is only a rough approximation, and it offers inconveniences as regards the fineness of the printing.

The present invention relates to a device which assures in an automatic manner, during the printing period, the exact equality of the periphery speeds of the printing cylinder and the pressure cylinder, so that no change need be made in the diameter of the pressure cylinder and hence in the thickness of its facing.

The following description with reference to the appended drawings which are given by way of example shows an embodiment of the said invention.

Fig. 1 is a diagrammatic view which relates to the independent control of the pressure cylinder and the printing cylinder of a rotary printing machine adapted for hollow relief work, and Fig. 2 is a corresponding developed plan view.

Fig. 3 is a front view of the compensating mechanism.

Fig. 4 is a section on the line 4—4 of Fig. 3.

Figs. 5, 6—7, 8—9, 10 are detail views of the mechanism on a smaller scale, respectively in front elevation and in section.

Fig. 11 is a diagram showing the operation of the mechanism.

The printing machine of the sunken relief type for sheet work, provided with a pressure cylinder, comprises as shown in Figs. 1 and 2 a pressure cylinder D and a printing cylinder A having half the diameter of the former and 60 rotating in contact therewith. The pressure cylinder makes but one revolution while the printing cylinder makes two.

The pressure cylinder is driven from the flywheel shaft through the medium of the 70 gear wheel C which engages a gear wheel secured to the said pressure cylinder.

The rotation of the printing cylinder A is effected indirectly by the same wheel C, through the medium of the compensating device, the object of the present invention, 75 which is shown diagrammatically by the circle B in Fig. 1.

In this manner there is no direct gear engagement between the pressure cylinder and 80 the said printing cylinder.

The principle of the compensator, the object of the invention, is as follows:

It should be noted in the first place that in the machine herein employed, the printing 85 takes place only during each alternate revolution of the printing cylinder.

In these conditions, the compensating apparatus will automatically assure a periphery speed for the printing cylinder which is equal 90 to that of the pressure cylinder during the operative or printing revolution of the said printing cylinder.

Should there be produced an angular displacement, to the front or rear, of the position 95 of the cylinder relatively to the position which it would occupy if its diameter were the same as that of the pitch circle, and hence relatively to its driving wheel, during the second revolution of the printing cylinder, 100 the said compensator will take up this difference, so that the printing cylinder will make two complete revolutions while the pressure cylinder makes one revolution.

A constructional form of the said compensator B is shown in Figs. 3 to 10.

Upon the main frame 2 of the printing machine is mounted a short horizontal shaft 1, it being secured for example by means of the nut 3 which is screwed to the threaded end 110

1^a of the said shaft and presses the washer 3^a against the frame 2.

The end 1^b of the shaft 1 serves to support the said compensating device.

5 This latter comprises a stationary disc 4 which is mounted upon the part of the shaft 1^b and is secured to the machine frame by the bolts 5; in the disc 4 is formed a slot constituting a cam 4^a (Fig. 5) having a suitable outline, such as the one shown in Figs. 3 and 5.

10 In the said cam slot is movable a roller 6 disposed upon an axle 7, mounted in the plate 8 which is bored to a diameter larger than that of the shaft portion 1^b. The said plate 15 carries, diametrically opposite the roller 6, a tenon 12 which is radially slidable in a guide slot 11^a formed in the gear wheel 11, which is loosely rotatable on the journal portion 1^b. The gear wheel 11 receives a uniform movement of rotation from the main driving element of the machine, i. e. it is in gear engagement with the wheel C (Fig. 1).

15 The plate 8 carries, on the tenon 12, a sliding member 10 which cooperates with the guides 13^a formed in the recessed plate 13 which is secured to the second gear wheel 14, loose on the journal portion 1^b and in gear engagement with the printing cylinder A (Fig. 1). The said parts are secured together by means of a circular boss 19 formed upon the said plate, which is inserted into a corresponding recess or bore in the wheel 14, and also by the two nuts 15 (Fig. 3); however, as shown in Fig. 3, the plate 13 is 20 provided with two slots 16 which are centered upon the axis of the boss 19, so that the plate may be given an angular displacement relatively to the wheel 14 about the said axis 19, whose value α on either side of the line A—A 25 may be observed by means of the pointer 17 which is movable before a suitable graduated scale formed upon the front face of the wheel 14. A knob 18, mounted on the said plate, allows the latter to be seized for effecting the 30 angular displacement of the plate. The proper position of the said plate having first been calculated, and then adjusted according to the indication of the pointer 17 and the graduated scale, as will be further discussed, the nuts 15 are screwed down, and the plate 13 is then secured to the gear wheel 14.

35 The two wheels 11 and 14 which are mounted in the adjacent position upon the journal 1^b are maintained in place by the washer 20 which is mounted on the end of the shaft and is held in position by the lubricating nut 21.

The operation of the apparatus is as follows:

40 The wheel 11 is actuated at a uniform speed of rotation by the wheel C. By means of the tenon 12 it actuates the plate 8 whose other end—through the medium of the roller 6—is guided by the face of the cam 4^a of the 45 stationary disc 4. The plate 8, when rotating,

will thus be given a radial sliding motion in the slots 11^a of the wheel 11, so that the lever arm 7 for actuating the plate—which is represented by the distance between the axis of rotation of the wheel and the axis of the tenon 12, will be periodically variable, the period being one revolution of the wheel 11.

45 The sliding member 10, which moves between the guides 13^a, will draw the plate 13 with it in its rotation, and will participate in the radial sliding of the tenon 12 with which it is in line. In this manner the lever arm 7 for the entraining of the said plate and of the wheel 14 which is connected therewith—which lever arm is represented by the distance between the axis $y-y$ of the boss 19 and the axis of the shaft 1—will vary at each instant. If it be supposed that the plate 13 is so mounted upon the wheel 14 that its plane of symmetry shall pass through the axis of shaft 1 (position of Fig. 3) it will be readily observed that the rotation of the wheel 14, actuated by the roller 10, will be uniform.

50 The whole action takes place as if the two gear wheels 11 and 14 were secured together.

55 But if the plate 13 is given an angular displacement relatively to the wheel 14 by turning said plate through an angle α about its pivot boss 19, the guide 13^a will no longer have the radial direction (Fig. 11), so that the center of the slide 10 will be displaced, during a complete revolution of the actuating wheel 11, between two limiting positions D⁰ and D¹ considered with reference to the wheel 14. If one commences to turn the whole device from the moment at which the roller 6 is at the point 6^a of the slot 4^a nearest the axis 1, the slide 10 will now have the position D⁰ (Fig. 11).

60 When the wheel 11 has made half a revolution the printing cylinder A will now have made a complete revolution. At this time, the angular spacing of the toothed wheels 11 and 14 is a maximum.

65 The slide actuating the wheel 14 has now attained the position corresponding to the point of the slot 4^a which is farthest from the axis 1. During the next revolution, the printing cylinder will not print. The apparatus then returns to the initial point D⁰ in order to recommence the cycle whose period is represented by two revolutions of the printing cylinder A. It will be noted that between the positions D⁰ and D¹ of the slide 10, two points on the wheels 11 and 14, which coincided at the beginning, will now be spaced apart by the quantity $d^0 d^1$ which represents the difference between the pitch circle of the toothed wheel keyed to the shaft of the printing cylinder, and the exact circumference of the said printing cylinder.

70 Otherwise stated, during half a revolution of the wheel 11, which rotates at constant speed, the wheel 14 will also be rotated at 130

a constant speed, but this will be higher than the speed of the wheel 11, so that the periphery speed of the printing cylinder A actuated by the wheel 14 will be exactly equal to the 5 periphery speed of the pressure cylinder D, but during the next half-revolution, the wheel 14 will be driven at a reduced though constant speed, the differences (either way) between the speeds during the half-revolutions 10 being exactly equal, so that the wheels 11 and 14 will be again in the same relative angular position at the end of a complete revolution of the wheel 11.

The value of this difference in speed is exactly 15 given by the length $d^0 d^1$, and it depends upon the inclination or the angular displacement of the plate 13 with reference to the wheel 14 about the pivot boss 19. It will be an easy matter to record opposite the pointer 20 17, on either side of the line 4—4, the indications which will permit of giving to the plate 13, without repeated trials, the proper inclination depending upon the new disposition of the printing cylinder.

Obviously, the application of the aforesaid 25 compensating mechanism is not limited to a machine for printing in hollow relief as herein disclosed by way of example, but it may be utilized with all types of printing or like 30 machines in which the rotating cylinders must be given a periphery speed which is periodically and momentarily different from the speed of the pitch circle of the actuating gear wheels to which they are secured.

What I claim is:

1. A compensating device for periphery speeds, comprising a first wheel which is actuated at constant speed, a second wheel having the same axis of rotation as the first, a cylinder mechanically connected with the second wheel and adapted to be actuated at variable speed, adjustable means for mechanically actuating the second wheel from the first wheel, said regulable means comprising 40 a disc coacting with the first wheel, means to impart to the disc, in addition to a rotary movement, a movement of translation in its plane, means connected with the disc and adapted to drive the second wheel, means 45 for driving the second wheel, adjustably connected with said second wheel and slidably engaging said disc, whereby slide movement of the disc is converted into an additional rotation of last mentioned means and of the second wheel, for an amount which may be varied at will by adjusting said means upon the second wheel.

2. A compensating device for periphery speeds, comprising a first wheel which is actuated at constant speed, a second wheel having the same axis of rotation as the first, a cylinder mechanically connected with the second wheel and adapted to be actuated at variable speed, a disk co-acting with the first wheel, 50 means for actuating the disk by the constant

speed wheel and for imparting to said disk a movement of rotation and also a sliding movement in its own plane, the said disk resuming the same position after a revolution of the wheel, a member having a slot formed 70 therein which member may be connected with the second wheel, means for driving the second wheel by means of the disc, said means being connected with the disc and slidable in the said slot, and means for varying the 75 inclination of the said slot with reference to the radial direction on the second wheel, whereby the second wheel will be actuated during half a revolution at a greater speed than the first wheel by a quantity which is so variable according to the inclination of the said slot, whilst during the other half of the revolution the speed of the second wheel will be less than that of the first wheel by the same variable quantity.

3. A compensating device for periphery speeds, comprising a first wheel which is actuated at constant speed, a second wheel having the same axis of rotation as the first, a cylinder mechanically connected with the second wheel and adapted to be actuated at 90 variable speed, a disk coacting with the first wheel, means for actuating the said disk by the constant-speed wheel and for imparting to said disk a movement of rotation and also 95 a sliding movement in its own plane, the said disk resuming the same position after a revolution of the wheel, a plate which is applied against the second wheel and comprises a vertical slot, means for displacing the said plate 100 relatively to the second wheel whereby the said slot may be inclined from the radial direction, means for driving the second wheel by means of the disc, said means being connected with the said disk and adapted to 105 slide in the said slot in the plate in such manner that the said plate will be rotated, means whereby the said plate may be connected with the second wheel in all angular positions of the plate, in such manner that the speed of 110 the second wheel will be greater than that of the first wheel by a certain quantity during half a revolution and will be less than this speed by the same variable quantity during the other half of the revolution.

4. A compensating device for periphery speeds comprising a first wheel which is actuated at a constant speed, a second wheel having the same diameter and the same axis of rotation as the first, a third wheel actuating a cylinder of variable speed and in gear engagement with the second wheel, a stationary plate, having a groove formed therein, a roller movable in the said groove, a rotatable and slidable plate carrying the axle of the said roller, a tenon mounted upon the said plate in the diametrically opposite position with reference to the said roller, a slot formed in the first wheel and coacting with the said tenon, a slide carried by the said tenon, a 120 125 130

plate wherein the said slide is movable in a pair of guides, and adjustable means whereby the said plate is held in position against the second wheel.

5. A compensating device for periphery speeds, comprising a first wheel which is actuated at a constant speed, a second wheel having the same diameter and the same axis of rotation as the first, a third wheel actuating a cylinder of variable speed and in gear engagement with the second wheel, a stationary plate, a groove formed therein, a roller movable in the said groove, a rotatable and slidable plate carrying the axle of the said roller, a tenon mounted upon the said plate in the diametrically opposite position with

reference to the said roller, slot formed in the first wheel and coacting with the said tenon, a slide carried by the said tenon, a plate wherein the said slide is movable in a pair of guides, an axle or journal secured to the said plate and coacting with a bore or recess formed in the second wheel, means for the angular displacement of the said plate relatively to the second wheel by pivoting said plate upon the said journal, means for securing the said plate to the second wheel in the proper position, and means for indicating the amount of the angular displacement.

In testimony whereof I have signed my name to this specification.

JEAN PERDREAU.
